UNITED STATES PATENT OFFICE.

FERDINAND VON MADALER, OF WEST DRAYTON, ENGLAND, ASSIGNOR TO THE ROTARY PHOTOGRAPHIC COMPANY LIMITED, OF LONDON, ENGLAND, A CORPORATION OF GREAT BRITAIN.

FILM-CARRIER.

1,100,591.

Specification of Letters Patent. Patented June 16, 1914.

Application filed May 18, 1912. Serial No. 698,186.

To all whom it may concern:

Be it known that I, FERDINAND VON MADALER, a subject of the Austro-Hungarian Emperor, residing at West Drayton, in the county of Middlesex, England, have invented a new and useful Improvement in Film-Carriers, of which the following is a specification.

This invention relates to roll film or strip carriers for kinematograph or like machines of the type described in my co-pending application filed 24th April 1912 under Serial No. 763434, wherein a carrier, containing a film, may be inserted or removed from the machine to provide a change of subjects or films, without any handling of the film or strip. According to this invention these carriers, which are primarily intended for use in connection with the projection of positive film pictures, though applicable for taking negative film pictures, comprise a case or guard, preferably of metal so as to render same fireproof, which contains and protects the film or strip when the latter is not in use and during the various manipulations preceding its sale and delivery as well as during its use and which adds so little to the cost of the film or strip that the latter can be retailed or sold therewith, such holder being adapted for immediate service in the machine without preliminary adjustment, as a mount or support for the film. The carrier is furnished with a light shaft situated between and entirely separating the two spool chambers and serves for the passage of the rays of light. The picture aperture is placed at one end of and coincident with said light ray opening so that a film or the like, can, if it is an exposed one, be projected by light transmitted through it while contained in the carrier. One of the chambers is also provided in the wall thereof and near the picture aperture with a cavity or embayment for housing the means, such as a sprocket wheel for example, for moving the film band with an intermittent motion past the picture aperture. Such a case or guard may be a closed one except for the opening through same or it may be a framework only if sufficient for the purpose. If closed it presents the advantage of affording protection to the film from fire, dust, scratching or handling except at the point of the throughway or opening where the fire could be localized as by

gripping rollers. A carrier or case thus constructed is rendered capable of being operated in a kinematograph or projecting machine of the type referred to by providing it with rollers preferably carried by suitable spindles to support the film such rollers being available from the outside of the casing or guard through means such as a bent pin, spindle, crank, holes or the like for connection with a part of the driven mechanism of the machine. Both rollers are preferably so provided to enable the travel of the film to be reversed. The carrier is thus self-contained; that is to say, it is at all times complete with its various parts consisting of film, or strip, rollers, spindles, and means for connection with or engagement by the mechanism of the kinematograph or like machine, and is adapted to be dropped or inserted easily into the machine so that the film or strip passes over the driving mechanism or sprocket-wheel, or removed from the machine without any preliminary operations or adjustment. The carriers which are preferably of metal are made as light in weight and as slight in bulk as is possible compatible with the requisite strength and rigidity, and further, they are made so thin that they can be placed in an envelop for postal purposes.

It has been proposed to provide consecutive view cameras and projecting apparatus with a number of removable film or picture strip boxes having sight holes through them prepared for use before they are placed in the camera or projecting apparatus but these have formed with them, or carry as a part of them, some of the mechanism of the camera or apparatus such as a part of the film driving means such mechanism, as well as the construction of one of the film rolls, necessitating the box being threaded on or inserted over two projecting driven spindles to give action to the parts in question. Such a box is necessarily more or less a part of the camera or projecting apparatus as it contains some of its mechanism and is thus not adapted to carry out the objects of this invention particularly the commercial aspect of same under which an inexpensive casing or guard is provided protecting the film during storage, sale or other handling and serving also as a mount for the film when it is being operated in the camera or other apparatus. It has also been proposed to en-

- tirely inclose the film or strip in a water tight two compartment carrier, the two compartments being connected by a narrow passage provided with a light ray opening, the 5 film or strip being driven from the center axles. Such a device is however of little practical use for the light rays passing through the water make the water hot with the result that the emulsion on the film 10 would be dissolved. According to another known construction, the film or strip and both spools, together with a part of the operative mechanism are entirely contained within a single chamber box.
- 15 In the accompanying drawing there are illustrated by way of example two forms of carriers according to the present invention. In this drawing Figure 1 is a plan of one form of carrier with the cover removed. 20 Fig. 2 is an edge view of same partly in section. Fig. 3 is a plan of a modified form, partly in section and Fig. 4 is an edge view. Referring first to Figs. 1 and 2 it will be seen that the carrier consists of a flat box 25 of approximately kidney shape in section composed of a body portion *a* and a cover *b* the central or neck portion having the open passage *c* through it, such passage being for sensitized films preferably provided with the internal walls *d*, *d*¹ which are continuations of the general side wall *d* of the body so that two separate chambers *A*, *A*¹ are provided to protect the two ends or parts of the film *e*. The walls *d*, *d*¹ provide preferably a wider opening at the rear end or that farthest from the lens, than at the front where the film may pass close to an opening *f* which is formed in the wall *d* and is preferably of the size of one of the film pictures. 30 The cover *b* has a corresponding opening. Inside the carrier are the film rollers *g*, *g* carried on spindles or pins *y*—*y* which are provided with bent portions or cranks *h*, *h* outside of the carrier body.
- 35 To enable the film to pass out easily from the holder a small guide roller *i* is mounted on a pin carried by the body portion and may project partly through an opening *j* in the wall *d* there being a corresponding opening in the cover *b*. To prevent the film being damaged the opening *j* in the body portion *a* may have one edge turned outwardly, as at *k* and protected by a piece of velvet or the like *l*. The carrier in the form shown 40 has also a recess or cut away part *m* formed in the walls of the body portion and the cover and also an opening *n* for the film to pass through such opening appearing also in the cover. The recess or the like in this case is adapted to receive the usual sprocket wheel *w* of the projecting or taking apparatus such wheel being for the purpose of propelling the film.
- 45 The body portion *a* and the cover *b* are substantially the same in construction the

latter having side walls *b*¹ inside of which the body portion passes so that the carrier is a substantially inclosed one. The form of film shown is provided with notches on its edges with which the two rows of pins of the sprocket engage. In this case the sprocket wheel draws the film from one roll past the opening *f* and a suitable part of the mechanism forming part of the machine described in my aforesaid co-pending application, such as an arm or pin engages one of the cranks *h* and winds the film onto a roller *g* the other crank *h* being put into engagement with a further pin when desired for rolling the film back again onto the roller *g* it started from. The recess *m* in the carrier enables it to be readily placed in position in the apparatus to bring the film into effective contact with the sprocket wheel and so that the film can be kept comparatively close to the opening *f*.

It will be obvious that various forms may be given to the exterior of the carrier or frame as well as to the parts directing the film or passage of light the constructions shown being by way of example only.

It will be obvious that the herein described carrier is suitable not only for what are sometimes termed "films" in the strictest sense of the word, implying transparency, but also for all analogous devices; and accordingly wherever the word "film" is used in the foregoing specification or in the following claims it is to be interpreted as including broadly any kind of strip or relatively long narrow piece of flexible material whether transparent or otherwise along which a row of pictures are or can be ranged and suitable for being mounted or contained within the herein described carrier.

What I claim is:—

1. In a film carrier for use in kinematograph apparatus, the combination of a box or container having two separate compartments, comprising top, bottom and sides adapted to contain and protect a film at any time and to support same when in use in a machine, each compartment of said carrier being entirely separated from each other by two walls which form by and between them an aperture for the passage of light, and means within each compartment of the carrier upon which the film is rolled and supported.

2. In a film carrier for use in kinematograph apparatus, the combination of a box or container having two separate compartments, comprising top, bottom and sides adapted to contain and protect a film at any time and to support same when in use in a machine, each compartment of said carrier being entirely separated from each other by two walls which form by and between them an aperture for the passage of light, and means within each compartment of the carrier upon which the film is rolled and supported.

carrier upon which the film is rolled and supported, and means connected therewith extending from within the carrier, whereby the film may be rolled or unrolled from outside the carrier, the carrier being provided with a recess adjacent to the point where the film passes between its supporting means so as to permit a driving sprocket to enter said recess to engage the film.

10 3. A film carrier comprising a box or container having top, bottom, and side walls, adapted to contain and protect a film, and having a passage therethrough bonded laterally by directing walls for the passage 15 of light, and an opening or window at the end of said passage corresponding to the size of picture for which the container is intended.

4. A film carrier comprising a box or 20 container having two compartments disposed in the same plane and divided from each other by two walls between which there is a clear passage through which light can travel, said compartments also having an 25 aperture each through which a film can pass from the interior of one to the interior of

the other, said apertures being so spaced that said film in its transit must pass transversely of the aforesaid passage.

5. In a film carrier the combination of a 30 container comprising two rigidly connected compartments in a common plane and each having top, bottom and side walls, said side walls being spaced apart intermediate the two compartments and so formed as to comprise between them a straight passage 35 through which light can pass; a spindle in each of said compartments; and a film having its opposite ends carried by said spindles, said compartments having apertures 40 disposed one on each side of said passage to permit the film to pass from the interior of one compartment to the interior of the other compartment across said passage.

In witness whereof I have hereunto set 45 my hand in the presence of two subscribing witnesses.

FERDINAND von MADALER.
